CLAIM

The ornamental design for a wall plate cover for electronic device, as shown and described.

DESCRIPTION

FIG. 1 is a front, top, and left perspective view of wall plate cover for electronic device showing claimed design;

FIG. 2 is a back, top, and right perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a front, top, and left perspective view thereof, shown with environment;

FIG. 10 is another front, top, and left perspective view thereof, shown with environment in an alternate state; and, FIG. 11 is a cross-sectional view taken in the direction of line 11-11 shown in FIG. 10.

The short evenly spaced and long evenly spaced broken lines in the views are directed to environment and the long dash short dash broken lines and arrows are used to identify the cross-section view. The broken lines form no part of the claimed design.

1 Claim, 8 Drawing Sheets
